UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

REVERSING APPARATUS FOR REGENERATIVE FURNACES.

Application filed April 8, 1920. Serial No. 372,205.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Reversing Apparatus for Regenerative Furnaces, of which the following, together with the accompanying drawings, is a specification.

The present invention relates to the class of devices ordinarily known as reversing valves, that are used in connection with regenerative furnaces for the purpose of 15 changing the direction of the flow of the burning gases in the furnace.

The present invention partakes in part of the characteristics set forth and described in my United States Letters Patent No. 1, 20 408,946, dated March 7, 1922, and also in my copending application Serial No. 268, 391, filed December 26, 1918, both covering improvements in reversing apparatus for regenerative furnaces. In each of the 25 constructions therein described there is utilized, in connection with certain of the flue terminals of the furnace, a swinging gravity closing cover, which is adapted to be opened automatically when the flue with which it is 30 associated is about to be connected to some other flue of the system. The present invention, while partaking generally of the nature of the inventions set forth and described in the aforesaid copending applications, in that it employs one or more of such 35 gravity closing covers, is distinguished radically from said prior inventions in respect to the construction and operation of the several flue connecting elements of the apparatus. In common with the mechanism set forth and described in the last named copending application, the present invention 40 contemplates the provision of duplicate reversing instrumentalities, each functioning 45 simultaneously with respect to both air and gas, but the operation of these reversing instrumentalities, as well as their general construction, differs radically from the reversing instrumentalities of said last named copending application. These differences are 50 fully set forth in the following description and pointed out in the annexed claims, ref-

erence being had to the accompanying drawings, in which—

Figure 1 is a diagrammatic plan view of 55 a regenerative furnace, equipped with reversing apparatus embodying the present invention.

Figure 2 is a sectional view, illustrating the construction of the reversing apparatus 60 shown in Fig. 1.

Figure 3 is a diagrammatic plan view similar to Fig. 1, showing a modification of the invention.

Figure 4 is a section taken on the line 65 4—4, Fig. 3.

Figure 5 is a section taken on the line 5—5, Fig. 3.

Figure 6 is a sectional view of still another modification of the invention. 70

Fig. 7 is a fragmentary view, illustrating a modification of the raising and lowering devices shown in Fig. 2.

Like reference characters refer to like 75 parts in the different figures.

Referring first to the construction illustrated in Figs. 1 and 2, the furnace 1 of the well known regenerative type is equipped at each end with the usual gas regenerator passages 2 and 2', and the usual air regenerator passages 3 and 3'. The flues 2, 3, and 2', 3', pass upwardly through the brick-work and terminate at the ground level; adjacent the terminal of each gas regenerator flue is disposed an alined terminal 4 or 80 4' of a gas supply flue, leading from a source of gas supply, not shown. Between each gas and air regenerator flue terminal is disposed an alined flue terminal 5 or 5', connecting with a main stack flue 6. Four alined and 85 symmetrically arranged flue terminals are thus disposed at each end of the furnace; the reversing instrumentalities for each end are identical in construction, and therefore it will be necessary to describe only one of 90 95 these instrumentalities.

As shown in Fig. 2, the four alined terminals of each set of flues, at each end of the furnace, are surmounted by a water seal casting 7, the latter being of sufficient depth 100 to enclose and contain a relatively deep body of water. The casting 7 provides a plurality of interior hollow extensions 8, 8, the latter being in register with the flue

2

terminals 2, 3, 4 and 5, and said extensions are completely surrounded by the body of water contained within said casting. For cooperation with the four extensions 8, 8, 5 of each set of furnace flues, the apparatus provides a movable reversing device 9, the latter having a sealing skirt 10 adapted to surround and inclose the entire set of extensions 8, when in lowered position, as 10 shown at the left hand side of Fig. 2. When either device 9 is in raised position, as shown at the right hand side of Fig. 2, the skirt 10 still maintains water sealed contact with the water of casting 7, but the several flue 15 terminals are uncovered so as to establish communication between them, as herein-after described.

Each device 9 in that part thereof which is superposed above the flue terminals 2 and 20 4, or 2' and 4', provides a hood or raised portion 11, this hood portion 11 being so disposed that when the device 9 is in lowered position, as shown at the left-hand side of Fig. 2, the flue terminals 2 and 4 are jointly 25 covered and inclosed by said portion 11 which forms a connection between them. The extension 8 of each gas flue terminal 4 or 4' is provided with the swinging cover 12 or 12' suitably pivoted to the pan 7, 30 each cover 12 or 12' having a projecting ear 13 which is adapted to be engaged by a lug 14, extending inwardly from the hood portion 11 directly above. When a device 9 is being moved into lowered position, the 35 contact of lug 14 with ear 13 opens the cover 12, as shown at the left hand side of Fig. 2. On the other hand, the initial lifting movement of a device 9 releases the lug 14 from the ear 13, and allows the cover 40 12 to close by gravity, thus shutting off and completely sealing the terminal of the gas supply flue when the device 9 is in raised position.

In the position of the parts illustrated in 45 Figs. 1 and 2, the direction of gases through the furnace is from left to right, as indicated by the arrows. The gas from the supply flue 4 enters beneath the hood portion 11 of left hand reversing device 9 and then passes 50 into the gas regenerator flue 2, traveling through the furnace toward the right. Air enters the flue 3 through an opening 15 in the left hand device 9, this opening 15 being controlled by a swinging damper 16 55 which is held open by a chain 17, or the like, adjustably secured to some fixed point. Obviously, when the device 9 is raised, the cover or damper 16 will close by gravity. The left hand stack flue terminal 5 is completely 60 isolated from the entering gas and air by the depending surrounding flange 18, which forms a seal with the water in pan 7.

The products of combustion leave the furnace by the right hand side, that is, 65 through the flue terminals 3' and 2' that

are uncovered, owing to the raising of the right hand reversing device 9. As shown at the right hand side of Fig. 2, the supply of gas through the flue 4' is completely shut off, due to the closure by gravity of the 70 swinging cover 12' associated with the extension 8 of this flue terminal. Consequently, all the burned gases, leaving by way of regenerator flues 2 and 3' pass into the space under the device 9 and make exit 75 therefrom through the stack connection flue 5'.

When it is desired to reverse the course of burning gases through the furnace, the left hand device 9 is raised, and the right 80 hand device 9 is simultaneously lowered. For this purpose the devices 9, 9, may readily be connected to windlasses or other suitable raising and lowering devices; for example, if desired, both devices 9, 9 may be 85 connected to a single windlass or other rotatable device 19, by means of cables 20 or the like, passing over guide pulleys 21, 21. When rotated in one direction the windlass 19 is adapted to raise one device 9 and lower 90 the other, and when rotated in the opposite direction, to lower the first device simultaneously with the elevation of the second device. Obviously, any other mechanism for simultaneously raising one device 9 and 95 lowering the other, may be adopted without departing from the spirit of the invention, as defined in the appended claims.

The elevation of the left hand device 9, and the simultaneous lowering of the right 100 hand device 9 effects the reversal of the furnace 1 in the following manner: The lowering of the right hand device 9 brings the projection 14 into contact with the ear 13 of swinging cover 12', thereby opening 105 the terminal of flue 4' to the interior of the hooded portion 11. At the same time, the flange 18 completely seals off and isolates the stack flue connection 5'. Likewise, the 110 damper 16 is opened to the air, so that air may enter the terminal of flue 3'. In this way the air and gas enter the furnace at the right hand side, by way of the gas flue regenerator passage 2', and the air flue regenerator passage 3'. The elevation of left 115 hand reversing device 9, Fig. 2, permits the instant closure of the swinging cover 12, thus preventing any wastage of gas from the supply passage 4. At the same time the air damper 16 also closes by gravity, and the entire volume of burned gaseous 120 products leaving the furnace by way of regenerator passages 2 and 3 is thus directed beneath the space inclosed by the left hand device 9 and its water sealing skirt 10, making 125 exit from this space by means of the flue 5 that connects with the stack, this flue being exposed because of the elevation out of operative relation thereto of the flange 18.

The modification of the invention as shown in Figs. 3, 4, and 5, embodies precisely the same construction and principle of operation as heretofore disclosed, with the exception that the furnace flue terminals instead of being alined, as in Figs. 1 and 2, are disposed in rectangular arrangement. That is to say, the furnace 1 is equipped with gas regenerator flues 22, 22', and air regenerator flues 23, 23'. The gas regenerator flues 22, 22' are disposed adjacent to and in alinement with the terminals of gas supply passages 24, 24', the latter being provided at their extensions 8, 8, as in the preceding case, with gravity swinging covers 12, 12'. Out of alinement with the aforesaid flue terminals, but in a parallel row therewith, the air regenerator flue terminals 23, are lined up with stack flue terminals 25, 25', as shown in Fig. 3.

Cooperating with the set of flues 22, 23, 24, 25 is a reversing device 26, of the construction shown in Figs. 4 and 5, and a duplicate reversing device 26' is employed in connection with the set of flues 22', 23', 24', 25', as shown at the right hand side of Fig. 3. These reversing devices 26, 26' are essentially the same in construction as the devices 9, 9, Fig. 2, except for the fact that each hood portion, designated 27 in Figs. 4 and 5, runs transversely of said device, instead of longitudinally. As before, each stack flue terminal 25 or 25', as the case may be, is adapted to be isolated completely by a depending flange 28 of its associated reversing device, and also as before the air is adapted to enter through a swinging gravity closing damper 29, which is held in open position, when the reversing device is lowered, by means of a chain or cord 30. In the position of the parts here illustrated, the passage of gases is from left to right through the furnace, the left hand device 26 being lowered, so as to hold the swinging cover 12 in open position, and the right hand device 26' being raised, whereby the associated cover 12', Fig. 3, is closed, so as to shut off and seal the gas supply flue 24'. The reversal of the furnace is accomplished by raising the right hand device 26' and lowering the left hand device 26, the same as in the form heretofore described.

Another modification of the reversing structure is shown in Fig. 6, where the same arrangement of flue terminals as shown in Figs. 1 and 2 is adopted. In the illustrated construction, a relatively shallow water seal pan 31 is superposed over the flue terminals 2, 3, 4 and 5, said pan having interior hollow extensions 32 in register with said terminals. A stationary inclosing structure 33 projects upwardly from the pan 31, and at its top provides an inner depending flange 34 adapted to form a water seal with the water in a trough 35,

surrounding the vertically movable reversing member 36. The latter is similar in construction to the members 9, 9, of Figs. 1 and 2, and works within the inclosing structure 33. A depending skirt 37 on the under side of member 36 is adapted to form a seal with the water in pan 31, and is also utilized to control the swinging cover 12 of gas supply flue 4. When the member 36 is raised, the seal is re-established by the immersion of flange 34 in trough 35.

When separate windlasses or raising and lowering devices are used, as shown in Fig. 7, for the movement of the reversing devices 9, 9, it is to be noted that either device 9, when in raised position, and serving as a passage for the exhaust gases to the stack, is adapted to be lowered more or less, without entirely shutting off the passage. Consequently said device at each end of the furnace, in addition to its function as a reversing instrumentality, serves also as a stack damper, and makes unnecessary the provision of the usual stack damper.

In this connection, it is to be noted that the above described throttling of exhaust gases, at that end of the furnace from which they may be discharged, is without effect upon the position of the reversing mechanism at the inlet end of the furnace, said reversing mechanism at said inlet end being necessarily maintained in the position illustrated at the left hand side of Fig. 2.

I claim,

1. The combination with the air, gas, regenerator and stack flues for each end of a regenerative furnace, of a reversing device for both air and gas associated with each set of flues and adapted in all positions to seal and surround the terminals of all the flues of said set.

2. The combination with the air, gas, regenerator and stack flues for each end of a regenerative furnace, of a reversing device for both air and gas at each end of the furnace in constant sealing relation to all of said flue terminals.

3. The combination with the air, gas, regenerator and stack flues for each end of a regenerative furnace, of a reversing device at each end of the furnace in constant sealing relation to all of said flue terminals, and means operable by the elevation of said reversing device for closing the gas supply flue terminal.

4. The combination with the air, gas, regenerator and stack flues for each end of a regenerative furnace, of a reversing device at each end of the furnace in constant sealing relation to all of said flue terminals, and means operable by the elevation of said reversing device for preventing the passage of air therethrough.

5. The combination with the air, gas, regenerator and stack flues for each end of a

- regenerative furnace, of a reversing device at each end of the furnace in constant sealing relation to all of said flue terminals, and means operable by the elevation of said reversing device for connecting the stack and regenerator flue terminals.
6. The combination with the air, gas, regenerator and stack flues for each end of a regenerative furnace, of a reversing device at each end of the furnace in constant sealing relation to all of said flue terminals, and means operable by the lowering of said reversing device for opening the gas supply flue terminal.
- 15 7. The combination with the air, gas, regenerator and stack flues for each end of a regenerative furnace, of a reversing device at each end of the furnace in constant sealing relation to all of said flue terminals, and means operable by the lowering of said reversing device for connecting the furnace with the gas supply.
8. The combination with the air, gas, regenerator and stack flues for each end of a regenerative furnace, of a reversing device at each end of the furnace in constant sealing relation to all of said flue terminals, and means operable by the lowering of said
- reversing device for isolating the stack flue terminal from the other flue terminals of the set.
9. The combination with the air, gas, regenerator and stack flues for each end of a regenerative furnace, of a reversing device at each end of the furnace in constant sealing relation to all of said flue terminals, and means operable by the lowering of said reversing device for procuring the passage of air therethrough to the furnace.
10. The combination with the air, gas, regenerator and stack flues for each end of a regenerative furnace, of a reversing device associated with each set of flues and adapted for movement to regulate the furnace draft.
11. The combination with the air, gas, regenerator and stack flues for each end of a regenerative furnace, of a reversing device associated with each set of flues and providing, in one position a passage from the furnace to the stack, and means for adjusting said reversing device to vary the size of said passage.

Dated this twenty-third day of March, 1920.

GEORGE H. ISLEY.
